[57] CLAIM

The ornamental design for a clamp, as shown and described.

DESCRIPTION

FIG. 1 is a perspective view of a clamp embodying the new design.

FIG. 2 is a plan view of the right side of the clamp shown in FIG. 1.

FIG. 3 is a plan view of the left side of the clamp shown in FIG. 1.

FIG. 4 is a front plan view of the clamp shown in FIG. 1.

FIG. 5 is a rear plan view of the clamp shown in FIG. 1.

FIG. 6 is a top plan view of the clamp shown in FIG. 1; and,

FIG. 7 is bottom plan view of the clamp shown in FIG. 1. The broken lines in the figures illustrate environmental subject matter and forms no part of the claimed design.
